J. H. MAYFIELD

CAR DOOR FASTENING DEVICE

Filed July 23, 1923

UNITED STATES PATENT OFFICE.

JOHN H. MAYFIELD, OF NORFOLK, VIRGINIA.

CAR-DOOR-FASTENING DEVICE.

Application filed July 23, 1923. Serial No. 653,261.

To all whom it may concern:

Be it known that I, JOHN H. MAYFIELD, a citizen of the United States, residing at Norfolk, in the county of Norfolk and State of Virginia, have invented certain new and useful Improvements in Car-Door-Fastening Devices, of which the following is a specification.

My invention relates to car door fastening devices.

The object of the invention is to provide means whereby car doors may be prevented from opening in transit which is frequently the case and is caused by the motion of the train and in starting and stopping, and to prevent such, pieces of wood are nailed at the ends of the doors when closed which ordinarily injures the car and its doors and is no more effective than driving large nails in the doors and frequently work apart.

A further object is to provide means whereby the doors may be wedged together firmly without injury to the car or its doors, or the doors may be separated at any distance and locked in that position in which case the ordinary box car may be used for transporting live stock, preventing their leaving the car and affording plenty of air.

A further object of the invention is to provide a positive fastening means so that they may be locked either closed or open, furnishing anti-friction means for the easy operation thereof, and also to provide for the sealing of the cars in a manner generally used by railway companies.

My device will enable one door to be tight against another, (in case of double doors), or close up to the door jamb, in single doors at all times as any lost motion or defective door construction will not interfere with the proper functioning of the device and is independent of any fixed point on the car proper.

Further objects and advantages will be more fully described herein and specifically pointed out in the claims hereunto annexed recourse being had to the accompanying drawing forming a part of this specification in which:

Figure 1 is a side view of a portion of a box car and its double sliding doors.

Figure 2 is a front view of my complete device without the end plates or covers.

Figure 3 is a cross section on the line 1—2 in Figure 4.

Figure 4 is a front view with the face or cover plate removed to show the interior arrangement.

Figure 5 is an end view of the device shown in Figure 4.

Figure 6 is a side elevation of the wedge block or chocking device.

Figure 7 is a front elevation of the same.

Figure 8 is a fragmentary portion of two parts of the device showing a modified form of anti-friction roller or wheel.

In the drawing like reference numerals indicate similar parts in all the several views.

In Figures 1 and 3, 1 represents the car body provided with the usual double sliding doors 2 and 3. The doors may be hung at the upper part of the cars near the eaves, in some type of cars, or upon a horizontal supporting bar or rail below the doors, as 4, and such is used to exemplify my invention. The rails 4 are suitably supported and extend the proper distance from the car body, by means of the extensions or brackets 5, Figures 1 and 3, or in any desirable manner.

6 is the main casting or element of my invention and has a flange 7 provided with holes 8 for the bolts for holding the same at the lower edges of the car doors 2 and 3.

10 is the front or face portion of the casting 6 and is provided with holes 10^a for the bolts 10^b for the same purpose as the bolts 9 and also to secure the hereinafter cover plate thereto.

The casting 6 is provided with a cored recess 11 and a larger recess 11^a both being connected to form one opening of different heights. The narrow recess is also provided with a semi-circular recess or seat 12 for the positioning of the roller or anti-friction wheel 13, and the larger recess, for the hereinafter described wedge or chocking block.

13^a is a central orifice in the roller 13 for the passage of the bolt or rod 14, Figures 2, 3 and 5, acting as its axle and for holding the two parts of my invention, that is to say, the casting 6 and its hereinafter named cover, together.

15 is a wedge shaped block horizontally slidable and liftably positioned in the larger recess 11^a and is provided with tapering chocking point or projection 16, a rounded rear bottom portion 17, and two laterally projecting lugs 18 and 19, one on each side

thereof and disposed at a slight angle to the horizontal plane of the block, as shown in Figures 6 and 7.

20 is the face plate or cover fitting over 5 the casting 6 and therefore encloses the roller 13 and the wedge or chocking block 15 within their respective cavities or recesses and secured by the bolts 10^a and 14 passing through the part 10 of the casting.

10 20^a are curved slots in the cover or face plate 20, also in the main casting 6, the latter being so placed in case the device is to be used in a reversed position.

In order to cover up the ends of my device 15 so as to completely enclose the same, I provide the end plates 21 having holes 22 therein, (Figure 3), for the bolts or screws 23. The end plates are also provided 20 with rectangular openings or orifices 23^a for the slideable mounting of the device upon the door supporting rail or rails 4, as shown in Figure 5.

24 is a bolt passing through the plates 6 and 20 and also through the lower or suspension 25 points of the car door, and which, at the same time, serves for the axle or fulcrum of the locking latch hook 24^a. The latch hook consists of the curved working faces 25, the flat portions 26 and the tapered nose or end 27 and such arrangement permits the hook to more effectually wedge itself upon the inclined faces of the wedge block lugs 18, as shown in Figure 2.

27^a is a staple or loop in alignment with 35 the portion 27 of the hook 24^a into which it enters and when in the proper place, the hole 28 is slightly below the staple so that the ordinary strap or wire car seal may be inserted and sealed at the lower edges of 40 the doors instead of at the middle portion thereof.

The hook 24^a is provided with a projection or lug 31 for receiving the impact of a hammer in order to disengage the hook 45 from the lug 18 and the staple 27^a.

In Figure 2, 29 represents the ordinary strap for the car seal 30, which is inserted in the orifice 28, as described.

At the top portion of Figure 4, the arrow 50 34 indicates the direction of the car door in opening and it will be seen that when the wedge or chock 16 of the block 15 is under the wheel or roller 13, it will be impossible for the latter to move or turn, inasmuch as 55 the hook 24^a is down and exerts pressure

against the lug 18 thus holding the wedge 16 under the roller, and as the block 15 is therefore immovable, the doors are effectually held at any point upon the rail 4.

To release the roller 13, the hook 24^a is 60 thrown upward as shown by the dotted lines in Figure 2, which moves the block 15 and wedge 16 to the right and clears the path of the roller and the doors can be readily opened.

The position of the chocking or wedge block when released from under the roller 13 and raised by the curvature of the slot 20, is shown by dotted lines in Figure 4.

When the chocking point 16, of the block 70 15, is raised by having the lugs 18 raised by being placed at the centre or at the right hand end of the slot, the rollers become the usual anti-friction means and the doors may be easily operated.

The dotted lines 33 in Figure 4, show a modified form of recess wherein a tapering upper surface is used, but I find that the arrangement shown by full lines is to be preferred.

In Figure 8 I show a modified form for 75 the rollers 13, if desired, whereby the rounded pins 32 are cast with the wheel or roller and introduced into correspondingly shaped cavities in the parts 6 and 20 which dispenses with the use of the bolt 14, as in Figure 3.

80 My invention is both cheap and efficient and locks the doors at any point along the rail 4 even if the abutting member expands or shrinks or has lost motion, my invention provided for closed doors at all times, when so desired, and no amount of jarring will loosen the wedge 16 as long as the hook 24^a is in place.

85 I claim:

In combination with sliding doors, of a recessed casting, roller or wheel supporting means in said recess, a wedge adapted to chock said roller supporting means against 90 movement, projection or lug means thereon, a curved slot for said lug or projection adapted to raise and lower said wedge, and hook or lever means adapted to engage said lug to prevent movement of said wheel supporting means.

100 In testimony whereof I have hereunto affixed my signature.

JOHN H. MAYFIELD.
